ELECTRIC SWITCH

Mannes N. Glickman, Nutley, N. J.

Application August 31, 1948, Serial No. 47,050

7 Claims. (Cl. 200—152)

1

This invention relates to electric switches of the liquid contact, mercury type.

Liquid contact circuit closers for controlling the flow of current have been constructed of a pair of electrically conducting, dished metal members electrically insulated from each other and hermetically sealed together by means of a peripheral bead of glass, and containing therein a pool of mercury. Additionally, a perforated carrier disc of ceramic material has been included as an element of such switches to permit the pool of mercury to electrically interconnect the dished members, in one position of the circuit closer and to split the pool of mercury to electrically disconnect the dished members in another position of the circuit closer. In making switches of this type, it has been necessary to carefully select the metal from which the dished members are to be formed in terms of its conductivity, adherence to vitreous materials, coefficient of expansion and reaction to mercury and gases. Also, the ceramic for the barrier disc as well as the glass for sealing the dished members, must be particularly selected so that the various diverse component parts of the circuit closer may be hermetically sealed together.

Accordingly, it is an object of this invention to provide a liquid contact switch body which is of a substantially all vitreous construction and includes a pair of juxtaposed, dished members which may be readily fused at their opposed contacting portions to form a hermetically sealed chamber, each of said members being provided with a metallic terminal hermetically sealed therein and so disposed as to extend to said chamber, said terminals also projecting exteriorly of said body whereby they may be engaged by a pair of opposed contacts, said chamber containing a pool of mercury which electrically interconnects the terminals in one position of the body, said pool of mercury being separated from said terminals and electrically disconnecting the same, in another position of the body.

Another object of this invention is to provide a liquid contact switch body comprising a pair of juxtaposed, circular dished vitreous members hermetically sealed at their peripheral portions, forming a chamber for containing a small quantity of mercury, each of the dished members having a metal terminal pin sealed into the wall transversely thereof, said pins being disposed eccentrically of the axis of the circular walls, the body being adapted to be mounted in a housing for rotation with said terminals disposed below the level of the mercury in the chamber in one

2

position of the body and above the level of the mercury in another position of the body, the terminal pins moving in an arcuate path during the rotation of said body.

5 A further object of this invention is to provide a liquid contact switch body comprising a pair of juxtaposed circular vitreous members fused together at their peripheral portions, said members being formed with similar recesses on their opposed faces so disposed as to form a hermetically sealed chamber disposed in eccentric relation to the axis of the walls, each of the members having a metal terminal sealed into the wall transversely thereof, the terminals being disposed at the axis of rotation of the body and being adapted to form pivot means for rotating the body whereby the chamber may assume different angular positions relative to the axis of rotation when the body is rotated about its terminals 20 as an axis.

Yet another object of this invention is to provide a switch construction comprising a housing and a liquid contact switch body mounted for rotation within said housing, the switch body comprising a pair of juxtaposed vitreous members sealed to each other at opposed portions thereof and formed to provide a hermetically sealed chamber for containing a small quantity of mercury, each of the members being provided with a metal terminal projecting exteriorly of said body, the housing comprising a pair of opposed walls, each of the walls being provided with an arcuate contact strip slidably engageable by one of the terminals on said body, and means on said walls to guide the movement of the body and the terminals during the rotation of the body, the contact strips including terminal connector portions extending exteriorly of said housing.

Still a further object of this invention is to provide a switch construction comprising a housing and a liquid contact switch body rotatably mounted within the housing, the switch body comprising a vitreous member formed with a hermetically sealed chamber interiorly thereof 40 for containing a pool of mercury therein, a terminal on opposite sides of the member including portions projecting into the chamber, each of the terminals being formed with similar arcuate guide means, the housing being provided with a pair 45 of opposed electrical contact members, each of the contact members including a projecting pin receivable in the guide means on the switch body whereby to guide the rotational movement of the switch body within the housing when the body 50 is rotated from a position wherein the terminals 55

are interconnected through contact with the pool of mercury to a position where the terminals are disconnected through disengagement with the pool of mercury.

Yet a further object of this invention is to provide a liquid contact switch body which may be fabricated from a minimum number of component parts, is easily manufactured, is economical to produce and yet is efficient to a high degree in use together with a switch housing particularly adapted for use with said switch body.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a vertical sectional view of a switch body embodying the invention;

Fig. 2 is a side elevational view thereof;

Fig. 3 is a vertical sectional view of a switch body embodying the invention and illustrating a modification thereof;

Fig. 4 is a side elevational view of the device shown in Fig. 3, in one position thereof;

Fig. 5 is an elevational view of the device shown in Fig. 3, rotated to another position thereof;

Fig. 6 is a vertical sectional view of a switch body embodying the invention and illustrating a further modification thereof;

Fig. 7 is an elevational view thereof;

Fig. 8 is a side elevational view of a switch housing and a switch body mounted therein;

Fig. 9 is a sectional view thereof;

Fig. 10 is a side elevational view of a contact member of the switch housing shown in Fig. 8;

Fig. 11 is a sectional view of a switch body embodying the invention and illustrating still a further modification;

Fig. 12 is a side elevational view thereof;

Fig. 13 is a top plan view of a contact member for use with the switch body shown in Fig. 11;

Fig. 14 is a sectional view of a switch body embodying the invention and illustrating a modification thereof;

Fig. 15 is a side elevational view of a switch body with a handle detachably mounted thereon and

Fig. 16 is an elevational view similar to that shown in Fig. 7, with the switch body rotated to its "off" position.

Referring in detail to the drawing and particularly to Figs. 1 and 2, 10 designates a switch body embodying the invention. The same comprises a pair of similar juxtaposed walled members 11 which are secured together to form a hermetically sealed chamber 12 between the members.

Each of the members 11 comprises a dished circular wall 13 from which there extends outwardly a peripheral portion 14. The members 11 are formed of molded vitreous materials such as glass. The members 11 are readily bonded together by fusion of the opposed faces of the peripheral portions 14.

The members 11 are provided with aligned terminal pins 15 hermetically sealed into the walls 13 and disposed transversely thereof. The inner

end of the pins 15 extend to the chamber 12 while the outer ends of the pins project exteriorly of the walls 13. As shown in the Figs. 1 and 2, the pins 15 are eccentrically related to the axis 5 of the circular walls 13. One of the pins 15 may be hollow to permit the exhaustion of the chamber 12, following the introduction of a small amount of mercury 17 into the chamber. The exhausted air is replaced with gas such as helium, nitrogen, carbon dioxide, or the like. The hollow pin is then suitably sealed.

A radially extending handle 18 may be fixed to the body 10 by having its inner portion suitably secured to a selected portion thereof. The handle may be of metal and fused to the vitreous members or it may be of non-metallic material, such as plastic or the like, in which case it may be cemented or otherwise secured to the vitreous members.

20 The switch body 10 may be mounted in a suitable housing provided with opposed contacts adapted to be interconnected in an electrical circuit and which may be engaged by the terminals 15 while said body is rotated through a predetermined angle by means of the handle 18 which is adapted to project exteriorly of the housing. It is understood that in one position of the body, the pins 15 are immersed in the pool of mercury 17, thereby electrically interconnecting the same to complete the circuit, while in another position of the body, the pins 15 will be disposed above the level of the mercury pool 17, as shown in dotted outline in Fig. 2, thereby electrically disconnecting the terminals and breaking the circuit.

To reduce arcing effects within chamber 12, the pins 15 may be in offset relation to each other, whereby on rotation of the body 10, only one of the pins 15 emerges from the mercury pool 17, to break the circuit.

In Figs. 3, 4 and 5 is shown a switch body 20 illustrating a modification of the invention. The same comprises a pair of similar juxtaposed circular vitreous members 21. Each of the members 45 includes a wall 22 formed with a recess 23 on one face thereof disposed eccentrically of the transverse axis of the wall. The members 21 further include oppositely disposed face portions 24. The members 21 are readily fused together at the opposed faces of the portions 24. The opposed recess 23 will thus form a hermetically sealed chamber 25. Metal alloy terminal pins 26 are hermetically sealed into the walls 22 transversely thereof. The terminals are disposed at the transverse axis of rotation of the body 20 and extend to a lower portion of the chamber 25 as shown in Fig. 4. The chamber 25 has a small amount of mercury 27 introduced therein through one of the pins 26 in the manner previously described. On rotating the body 20 about its terminals 26 as an axis, by means of a handle 28 extending from the body, from the position shown in Fig. 4 to the position shown in Fig. 5, the terminals will maintain their axial position while the mercury level will change from a position covering the inner ends of the terminals to a position uncovering the terminals, thereby electrically disconnecting the same.

In Figs. 6 and 7 is shown a switch body 30 similar to that shown in Figs. 1 and 2, except as hereinafter pointed out. The dished members 11 enclose a ceramic barrier disc 31. The disc 31 is of a thickness substantially equal to that of chamber 12 between the members 11 and 70 is formed on its opposite faces with recesses 32

which are interconnected by a transverse opening 33. The terminals 15 in walls 13 are disposed slightly out of alignment with opening 33. In one position of the body 30, the mercury 17 extends on either side of the disc 31 as well as in the opening 33 therein so as to electrically interconnect the terminals 15. On rotating the body 30 through a predetermined angle by means of handle 18, the opening 33 in the disc 31 will be above the level of the mercury 17 thereby dividing it into two separated pools and breaking the circuit between the terminals.

The switch bodies 10 and 30 may be mounted for rotation in a switch housing 40 which comprises a pair of walled members 41 in opposed relation. The members 41 may be formed with suitable recesses 42 to receive the switch body. The members 41 are further formed on their inner surfaces with arcuate grooves 43 for receiving the projecting terminals 15 on the switch body. Disposed within the grooves 43 are arcuate strips 44 of contact metal for making slidable contact with the terminals 15. The strips 44 may be formed with arcuate grooves 45 which will positively guide the pins 15 during their arcuate movement. Extensions 46 of the strips 44 project outwardly of the housing being provided with screws 47 to form terminal connectors. The handle 18 on the body projects through an opening 48 in the housing to permit rotation of the switch body through a predetermined angle. The rotation of the switch body makes or breaks the circuit in which the switch is connected, in the manner previously described.

The angular extent of the arcuate grooves 45 will determine the limits of rotation of said switch body and form stops to establish on and off positions of the handle 18.

In Figs. 11, 12 and 13 are shown a further modification of the invention. The same comprises a switch body 50 and includes dished vitreous members 11 which are hermetically sealed together to form a chamber 12 for containing mercury, as previously described. Each of the members 11 has secured to the outer face thereof, a terminal 51. The terminal 51 includes a portion 52 extending through the walls of members 11 and projecting into chamber 12. Each of the terminals 51 is further formed on its outer face with a pair of outwardly extending curved, concentric flanges 53 interconnected at their opposite ends to form an arcuate guide way 54.

The switch body 50 may be mounted for rotational movement in a switch housing similar to housing 40 except as hereinafter described. The housing walls are formed to receive contact members 61. The members 61 include pins 62 at right angles thereto which are engageable in the arcuate guide way 54 on terminals 51 of the switch body 50. The contact members 61 may be of spring metal, suitably biased toward each other to resiliently press the pins 62 against the terminals of the switch body and provide sliding contact therebetween. The members 61 also include terminal screws 63 for making suitable connections with the wiring with which the switch is associated.

In Fig. 14 is shown a switch body 70 which includes a pair of dished vitreous members 71 which are fused together to form a hermetically sealed chamber 72. Interposed between the members 71 is an annular metallic member 73 of T-shaped transverse cross-section. The member 73 becomes sealed between the fused members 71 and

provides an outer rim portion 74. The rim portion 74 may be used to secure a handle thereto for rotating the switch body. Also the rim portion 74 may provide a bearing surface for the rotatable switch body relative to the housing in which the switch body is mounted.

The dished vitreous bodies used in making the liquid contact switches referred to hereinabove, may be of glass or glassy material, having a suitable fusing point. The terminals fused into the dished members are made of suitable metals or metal alloys, well known in the art and selected in terms of the particular glass used in making the vitreous members, to insure the proper hermetic seal therebetween.

The switch bodies may be provided with one or more notches on peripheral portions thereof to attach handles having portions thereof removably engaged in said notches. Since the bodies 20 are of insulating vitreous material, the notch engaging portions of the handle may be of spring metal suitably flanged to engage the notches. Such an arrangement is shown in Fig. 15 wherein the peripheral portion of switch body 10 is formed with notches 80. A handle 18a includes a spring metal portion 81 with flanges 82 at opposite ends thereof which may be snapped into notches 80.

It will thus be seen that there is provided a device in which the several objects of this invention are achieved and which is well adapted to meet the conditions of practical use.

As various possible embodiments might be made of the above invention, and as various changes might be made in the embodiment above set forth, 35 it is to be understood that all matter herein set forth or shown in the accompanying drawings is to be interpreted as illustrative and not in a limiting sense.

Having thus described my invention, I claim 40 as new and desire to secure by Letters Patent of the United States:

1. A rotatable liquid contact switch body, comprising a pair of juxtaposed dished vitreous members fused together at peripheral contacting portions thereof to form a hermetically sealed chamber therebetween, a terminal mounted in each of said members with one end thereof extending into said chamber and the other end extending exteriorly of the member, and a quantity of liquid electrically conductive material within said chamber.

2. A switch body comprising a pair of juxtaposed dished vitreous members having contacting peripheral portions fused together, said members including spaced circular walls forming a hermetically sealed chamber, a terminal sealed into each of said members and extending transversely of said walls, and a quantity of electrically conductive liquid material in said chamber.

3. A liquid contact switch body comprising a pair of dished vitreous members fused together at opposed contacting marginal portions thereof, and forming a hermetically sealed chamber therebetween, and a rim member secured to peripheral portions of said body, said rim member including a flange disposed between portions of the opposed marginal portions of said dished members.

4. A liquid contact switch body comprising a pair of dished vitreous members fused together at opposed marginal portions thereof, and forming a hermetically sealed chamber therebetween, a terminal secured to each of said members and including a portion extending into said chamber, said terminals being aligned relative to each other, a barrier member disposed within said

chamber and forming a pair of compartments within the chamber, said barrier being formed with a transverse opening interconnecting said compartments, said opening being offset relative to said terminals, and liquid electrically conductive material within said chamber.

5. A rotatable switch body comprising a pair of dished vitreous dielectric members including contacting peripheral portions, said members being fused together at said contacting portions to provide a hermetically sealed chamber between said members, a terminal sealed into each of said members and including a portion extending to said chamber and a portion extending externally of said member, said externally extending portions of the terminals being adapted to provide means for mounting said body for rotation about a transverse axis thereof, and a quantity of electrically conductive liquid material in said chamber, said terminals being disposed relative to the axis of rotation of said body whereby rotation of said body through a predetermined angle provides movement of at least one of said terminals from a position below the level of the liquid

material in said chamber to a position above the level thereof.

6. A switch body as in claim 5 wherein an axis extending through at least one of said terminals is spaced from the rotational axis of said body.

7. A switch body as in claim 5, wherein an axis extending through said terminals coincides with the rotational axis of said body.

MANNES N. GLICKMAN.
